UNITED STATES PATENT OFFICE.

WILLIAM BUTTLER, OF REDKEY, INDIANA.

FURNACE FOR FIRE-FINISHING GLASSWARE.

SPECIFICATION forming part of Letters Patent No. 633,985, dated October 3, 1899.

Application filed January 5, 1898. Serial No. 665,648. (No model.)

To all whom it may concern:

Be it known that I, WILLIAM BUTTLER, of Redkey, in the county of Jay and State of Indiana, have invented a new and useful Improvement in Furnaces for Fire-Finishing Glassware, of which the following is a full, clear, and exact description, reference being had to the accompanying drawings, forming part of this specification, in which—

10 Figure 1 is a front elevation, partly in section, of my improved furnace. Fig. 2 is a top plan view of the same, and Fig. 3 is a broken side elevation showing additional mechanism for giving rapid rotation to the glass articles.

15 My invention relates to the fire-finishing or glazing of the ends of glass articles, and is designed to provide an improved furnace by which this operation may be easily and quickly carried out.

20 In the drawings, 2 represents the furnace proper, which consists of a semi-annular shell lined with refractory material and preferably provided with an intermediate concentric partition 3, which divides the furnace-chamber into two separate portions. Into each of 25 these furnace-chambers thus formed project a series of gas-burners 4 and 5, respectively, the heated products from which escape through the arc-shaped slot 6 in the top of 30 the furnace. To carry the ends of glass articles through this curved slot, I provide the central vertical shaft 7, actuated by beveled gear 8 and provided with horizontal carrying-arms 9. At the outer end of each of these arms 35 is provided an annular holder 10, adapted to receive a loose flanged ring 11, having projecting radial pins 12. These pins are arranged to contact with suitable pins 13 upon a semicircular rack 14, so that as the shaft 7 is 40 slowly rotated the rings 11 will move in a circular path over the slot and the rings will be rotated during such movement, thus rotating the chimneys or other articles 15, which hang within the rings. In some cases the chimneys 45 or glass articles are made slightly heavier on one side than on the other, and if these articles were rotated during the fire-finishing the thin side would come out shorter than the heavy side. To prevent this and to glaze 50 both sides equally, I employ plain rings, which are placed in the holders 10, instead of the rings having projecting pins, and arrange

the gas-burners so that the heat will be more intense at one side of the partition-wall than on the other. The operator may then place 55 the chimneys in the holding-rings so that the thicker side will be exposed to the greater heat, the article passing through the slot without rotation. In place of either form of these holding-rings, where it is desired to give 60 a higher speed of rotation to the article, I may employ the mechanism of Fig. 3. In this figure 7' represents the central shaft, provided with lower arms 9' and upper arms 9''. The outer ends of the arms 9' are slotted and 65 provided with upwardly-extending lugs 16, which are arranged to contact with rings 17, secured to the handles 18 of the snaps, which hold the glass articles at their lower ends. The upper end of each handle is squared and 70 engages a square hole in a chuck 19. This chuck is mounted at the lower end of a short shaft carried in the upper arm and provided at its upper end with a pinion 20, engaging a toothed wheel 21 upon a second shaft, also 75 carried on the arm, and which is provided with a pinion 22, engaging a semicircular rack 23. In placing the snap in position the operator forces its squared upper end into the square hole in the chuck and then allows 80 the snap to drop slightly, so as to bring the collar 17 behind the stop 16, so that the snap will be held in place and be given a high speed of rotation by the multiplying gearing connected to the chuck. 85

The operation is apparent. The articles being inserted either in the holding-rings or in the snap are moved with their lower ends within the slot of the furnace and these ends are thus sufficiently heated to remove the 90 sharp edge thereof, while the heated currents of air rising around the body of the article partially anneal the same and prevent breakage. The articles may be rotated either at a high or low rate of speed or may be moved 95 through the slot without rotation, the heat of the slot being regulated, as desired, on each side of the partition.

The advantages of my invention result from the fact that the articles may be fire-finished 100 much more quickly than before and without the use of expensive and slow labor therefor. The semicircular form of the furnace renders the arrangement for giving rotation to the

articles simple and compact and enables the central shaft with carrying-arms to be employed.

Many changes in the form and arrangement of the parts may be made without departure from my invention, since

What I claim is—

1. A fire-finishing furnace having a slot in its top extending substantially in the arc of a circle, and a rotatory shaft having arms provided with holders above and exterior to the furnace and arranged to support the articles in a vertical position with their lower ends within the slot; substantially as described.

15 2. A fire-finishing furnace having an elongated slot, said furnace having an inner longitudinal partition-wall and burners on both sides of the wall whereby the heat may be regulated to different degrees on opposite sides thereof substantially as described.

20 3. The combination with a furnace having in its top a slot extending substantially in the arc of a circle, of a rotatory shaft having lateral carrying - arms provided with holders above and exterior to the furnace and arranged to support the articles in a vertical position with their lower ends exposed to the heat within the slot, and mechanism for rotating said holders during their movement; 25 substantially as described.

4. The combination with a furnace having in its top a slot extending substantially in the arc of a circle, of a rotatory shaft having arms provided with holders above the furnace and arranged to hold the articles with their lower ends subjected to the heat within the slot, an arc-shaped rack, and gear connections between the rack and the holders and arranged to rotate the same during their movement over the slot; substantially as described.

5. A fire-finishing furnace, having a longitudinal slot in its walls, a removable snap, means for holding the snap with the inner end of the article in the slot, and mechanism for moving the article through the slot; substantially as described.

6. A fire-finishing furnace, having an elongated slot, a removable snap, supports arranged to hold the snap with the inner end of the article in the slot, and mechanism for rotating the snap and moving it longitudinally of the slot; substantially as described.

In testimony whereof I have hereunto set my hand.

WILLIAM BUTTLER.
